WELL FISHING TOOL

Joe E. Nichols, Coalinga, Calif.

Application September 27, 1938, Serial No. 231,925

6 Claims. (Cl. 294—88)

This invention relates to a fishing tool for recovering small articles, such as drill bit cones, from the bottom of deep wells and particularly refers to a device which is actuated by fluid or hydraulic pressure through the conventional string of drill pipe and is positively controlled from the drilling floor at the surface of the earth.

During the drilling of deep wells, particularly with cone type bits or others having small parts, there may accumulate in the bottom of the hole 10 a number of such parts, usually of very hard substances, which materially hinder drilling operations. This invention comprehends broadly a fishing tool which may be run to the bottom of the hole on a conventional string of hollow drill pipe and there be actuated by hydraulic pressure applied by the drilling fluid, compressed air, or gas, to extend downwardly a plurality of spring fingers to surround and grasp the so-called "fish" and retain it so that it may be withdrawn from the well.

A further object of the invention is to provide a simple and inexpensive fishing tool that will automatically indicate to the operator whether or not the fish has been secured.

Another object is to provide a hydraulically actuated fishing tool that will permit drainage of drilling mud or fluid from the drill pipe as the latter is withdrawn from the well bore.

Another object is to provide a fishing tool that may be repeatedly actuated at the bottom of the well so that if the fish is not secured at the first attempt the device and the drill pipe supporting it will not have to be taken out of the well to be reset.

These and other objects and advantages will be more fully apparent from the following description and from the accompanying drawing, which forms a part of this specification and illustrates a preferred embodiment of the invention.

In the drawing,

Figure 1 is a longitudinal sectional view of a fishing tool constructed according to this invention, with the operating parts in their retracted position.

Figure 2 is a longitudinal sectional view of the same device shown in Figure 1, with the parts in extended position ready to surround and pick up the fish.

Referring to the drawing, and particularly to Figure 1, reference numeral 10 designates the generally cylindrical body of the device, which is usually reduced in diameter at 11 and is threaded at 12 to receive a correspondingly

threaded tool joint of a conventional string of drill pipe, by means of which the device is inserted into and withdrawn from the well bore. The bore 13 of body 10 is preferably smoothly finished and extends from an upper shoulder 14 to a lower threaded section 15, the latter adapted to receive a similarly threaded guide bushing 16 which may retain the operating parts in the body. Near the upper end of bore 13 are one or more fluid ports 17 which are normally closed off by a tubular valve 18 when the device is being run into the well bore in its retracted position.

Valve 18 rests upon or is secured to a piston generally designated 19, and which is composed of an upper plate 20, a resilient packing 21, and a lower plate 22, the plates being secured together as by bolts 23. Upper plate 20 is preferably recessed as at 24 and is provided with a central downwardly extending wash pipe or tube 25, the latter extending through piston 19 and being provided at its upper end with a seat 26 for a valve member such as a ball 27, the purpose of which will be described below.

Extending downwardly from piston 19, and in this case from lower plate 22, are a plurality of circumferentially spaced resilient or spring fingers 28, shaped substantially as shown and, in their retracted position illustrated in Figure 1, being compressed together and retained at their lower ends by the bore 29 of bushing 16. In order to retain valve 18, piston 19, and spring fingers 28 in their retracted position, there is provided an elastic means such as springs 30 and 31, guided by members 32, 33 and 34, all of which move freely within bore 13 of body 10. These springs are preferably of such size that they will exert a considerable force to urge the piston 19 and the fingers 28 upwardly, to displace outwardly through ports 17 any mud or drilling fluid that may be above the piston, and to securely hold any fish that may be grasped by that portion of spring fingers below bushing 16.

The lower end of body 10 is preferably notched or serrated as at 35, so that it may be used to drill through minor obstructions or so-called "bridges" in the well bore, and also to agitate cuttings that may have settled around the fish so that such cuttings may be removed and washed upwardly by fluid passing through the wash pipe 25. Also, it is desirable that bushing 16 be spaced somewhat above the bottom of body 10 to form a chamber into which the fish may enter during such cleaning operations and into which said

fish may be drawn while the device is being removed from the well bore.

In operation, the body 10, in the condition shown in Figure 1, is attached to the lower end of a conventional string of drill pipe, to which is connected the usual mud fluid pumps, rotating and hoisting means and other apparatus used for rotary drilling, and the tool is lowered to the bottom of the well bore. Bridges or other obstructions are cleaned out by rotating the tool and circulating mud fluid, gas, or water downwardly through the drill pipe and through wash pipe 25. Springs 30 and 31 serve to keep the piston 19, valve 18 and fingers 28 in their upper or retracted position during such operations. After cavings or cuttings have been washed or blown away from around the fish to be recovered, the tool is lifted a few feet off bottom, and ball valve 27 is dropped into the drill pipe, passing downward through the mud fluid until it rests on seat 26 of piston 19. The tool is then lowered nearly to bottom, the distance above the bottom being about the distance to which spring fingers 28 may be extended as shown in Figure 2. The pressure on the drilling mud, or whatever fluid pressure is being used to actuate the tool, is increased, driving piston 19 downwardly against the springs 30 and 31, and extending spring fingers 28 downwardly to surround the fish.

Some fluid will be released through ports 17 as soon as valve 18 moves downward from the position shown in Figure 1, and the area of these ports should be so proportioned to the fluid flow that adequate pressure drop therethrough will be provided to compress springs 30 and 31 to the desired point.

The tool is then lowered a slight amount to bend inwardly the lower ends of fingers 28, after which the pressure on the actuating fluid is released. This will permit the springs 30 and 31 to expand, raising the piston 19, valve 18 and spring fingers 28, the latter being squeezed together by the bore 29 of lower bushing 16 to constrict the fingers about the fish. If the operation is not successful, valve 18 will be raised by piston 19 and springs 30 and 31 to its original position to cover ports 17, and this will be indicated to the operator by failure of the liquid level in the drill pipe to fall when the latter is raised. The operations just outlined, namely, increasing the pressure to extend fingers 28, followed by a release of pressure to retract the latter, may be repeated until the fish is secured, without removing the entire tool and string of drill pipe from the well bore.

If the fish is caught by the lower ends of fingers 28, it will prevent the latter from being drawn through bore 29 of bushing 16, so that piston 19 and valve 18 will be unable to move to their uppermost position. Ports 17 will thus be left open to drain the drill pipe, as successive lengths are removed from the well. If the fish is quite small, valve 18 may almost reach its uppermost position, in which case the unequally

disposed spaces between prongs 36 at the top of valve 18 will permit drainage through at least one of ports 17.

It is obvious that many alterations and changes could be made in the arrangement shown without departing from the essential features of the invention, and all such modifications as fall within the scope of the appended claims are embraced thereby.

I claim:

1. A well fishing tool comprising a tubular body adapted to be introduced into a well bore on a drill pipe, a piston in said body, a plurality of circumferentially spaced spring fingers extending downwardly from said piston and adapted to be extended out of said body when fluid pressure is admitted thereto above said piston, a spring urging said piston and said fingers toward their retracted position, a fluid passage through said piston, and means operable from the upper end of said drill pipe for controlling fluid flow through said passage.

2. A well fishing tool according to claim 1 with the addition of a drain port in said body above said piston and a sleeve extending upwardly from said piston for opening and closing said port.

3. A well fishing tool according to claim 1 with the addition of guide means in said body cooperating with said spring fingers, so constructed and arranged that said fingers will expand outwardly as they are extended from said body and will contract inwardly as they are retracted within said body.

4. A well fishing tool according to claim 1, in which the upper face of said piston is provided with a valve seat in said fluid passage, and said flow control means constitutes a ball adapted to be passed downwardly through said drill pipe to rest on said valve seat.

5. A well fishing tool according to claim 1 in which said body extends downwardly below said fingers when the latter are in their retracted position, to form a chamber into which said fingers may draw an object to be withdrawn from said well bore.

6. A well fishing tool comprising a tubular body adapted to be introduced into a well bore on a drill pipe, a piston in said body, resilient means adapted to urge said piston upwardly in said body, a plurality of curved resilient fingers movable by said piston and adapted to be extended downwardly below said body by the application of fluid pressure on said piston and to be retracted into said body by a release of fluid pressure on said piston, cutting means at the lower end of said body spaced from the lower end of said resilient fingers in their retracted position to clear an annular space below the object to be grasped by said fingers so that they may encircle the same when they are extended from said body, and guide means in said body spaced above the lower end of said fingers to contract the same inwardly as they are retracted by said piston.

JOE E. NICHOLS.
